UNITED STATES PATENT OFFICE.

JACOB K. WEED, OF PHILADELPHIA, PENNSYLVANIA, ASSIGNOR OF ONE-HALF TO S. TWITCHELL COMPANY, OF CAMDEN, NEW JERSEY, AND PHILADELPHIA, PENNSYLVANIA, A CORPORATION OF NEW JERSEY.

BOTTLE-FILLING MACHINE.

SPECIFICATION forming part of Letters Patent No. 703,870, dated July 1, 1902.

Application filed March 6, 1902. Serial No. 96,879. (No model.)

To all whom it may concern:

Be it known that I, JACOB K. WEED, a citizen of the United States, residing at the city of Philadelphia, in the county of Philadelphia and State of Pennsylvania, have invented certain new and useful Improvements in Bottle-Filling Machines, of which the following is a specification.

My invention has relation to a machine for filling into bottles particularly carbonaceous liquids and of a type in which the bottle is elevated and depressed, so as to be brought into and out of engagement with the filling-head of the machine, and in such connection it relates generally to the construction and arrangement of such a machine.

The principal object of my invention is to provide a simple and efficient bottle-filling machine which can be readily operated by unskilled labor and which is made independent and by proper manipulation of various mechanisms is adapted to automatically fill a bottle with a liquid under pressure.

My invention, stated in general terms, consists of a bottle-filling machine constructed and arranged in substantially the manner hereinafter described and claimed.

The nature and scope of my present invention will be more fully understood from the following description, taken in connection with the accompanying drawings, forming part hereof, in which—

Figure 1 is a front elevational view of the upper portion of the machine, partially sectioned, embodying main features of my invention. Fig. 2 is a rear elevational view of the upper portion of the machine, partly sectioned. Fig. 3 is a detail view, partly sectioned, illustrating in side elevation mechanism for controlling the openings of the liquid and sniff valves. Fig. 4 is an enlarged sectional view illustrating a bottle in engagement with the filling-head, the supporting table for the same, and draw-hook for the sealing device in front elevation. Figs. 5 and 6 are detail views of the draw-hook in side elevation, illustrating the different positions which the hook occupies before and after the raising of the sealing device for closing the

filled bottle. Fig. 7 is a top or plan view, enlarged and partly sectioned, of the supporting-table for the bottle and means connected with the table adapted to automatically control the actuation of a valve and pump for controlling the entrance of liquid and flavoring extracts or syrups into the bottle. Fig. 8 is a side elevation, partly in section, enlarged, of a portion of the left-hand side of the machine, illustrating means for controlling the entrance of liquid into the bottle; and Fig. 9 is a view, partly in section and partly in side elevation, of a pump for feeding flavoring extracts or syrups into the bottle and also of means for controlling the actuation of the pump.

Referring to the drawings, *a* represents a bed-plate supported by standards *a'* and *a''*, in which is supported a shaft *a³*, positively driven by a pulley *a⁴* and belt *a⁵* from any suitable source of power. (Not shown.) The shaft *a³* transmits its motion by means of gear-wheels *a⁶* and *a⁷* to a shaft *a⁸*, carried by bearings *a⁹* and *a¹⁰* of the standards *a'* and *a''*. To the shaft *a⁸* are secured a number of cams adapted to operate in proper succession mechanisms to fill the bottle with carbonaceous or other liquids and flavoring extracts or syrups and to relieve excess of gas-pressure from the bottle to enable the complete filling of the same, as will be hereinafter more fully explained. To the bed-plate *a*, and preferably by means of brackets *a¹¹* and *a¹²*, are secured two vertically-projecting rods *b* and *b'*, carrying at their free ends a horizontally-arranged yoke *b²*, which rods and yoke form a frame *B* for the support of the filling-head *C*, as illustrated in Figs. 1 and 2. The filling-head *C* consists of a socket *c*, which is held in position within the yoke *b²* by a nut *b³* and is provided with two laterally and oppositely arranged extensions *c'* and *c''*, in the interior of which are located conduits or passages *c³* and *c⁴*, communicating with a centrally-arranged filling-chamber *c⁵* in the socket *c*, as illustrated in Fig. 4. Below the filling-chamber *c⁵* and within the lower portion of the socket *c* is provided a rubber washer or gasket *c⁶*, which is removably connected with the

socket *c* by means of a nut *c*⁷. Directly below the filling-head *C* and within a suitable recess or opening in the bed-plate *a* is arranged a cup-shaped support *d*, provided with 5 two extensions *d*¹ and *d*², which are in sliding engagement with the fixed rods *b* and *b*¹ of the frame *B*, which rods serve as guides for the support *d*, as shown in Fig. 7. The cup-shaped support *d* is adapted to receive a disk 10 or table *d*³, upon which the bottle *e* to be filled is placed. This table *d*³ is held in position within the support *d* and normally in alignment with the upper edge thereof by means of springs *d*⁵, surrounding guide-rods *d*⁴, passing 15 through the bottom of the support *d*, as illustrated in Fig. 4. The rods *d*⁴, in conjunction with the support *d*, holding the table *d*³ in proper horizontal position within the support, are adapted to permit of the movement 20 of the table in a vertical direction. The under side of the support *d* is provided with a roller *d*⁶, engaging a cam *d*⁷, secured to the shaft *a*⁸, which cam during a certain portion of its revolution will raise the support *d* and 25 table *d*³ and bring the head *e*' of a bottle *e*, placed thereon, into engagement with the gasket *c*⁶ of the filling-head *C*, as illustrated in Fig. 4. The table *d*³, however, will follow this upward movement only as far as the height 30 of the bottle on the table and compression of the gasket *c*⁶ by the head *e*' of the bottle *e*, so that the table will be more or less depressed in its support *d* against the tension of the supporting-springs *d*⁵. By this arrangement 35 of the support *d* and table *d*³ it will be readily observed that bottles of varying heights or lengths may be employed, as the table will adjust itself to the height of the bottle. The passage *c*³ of the extension *c*' of 40 the socket *c* of the filling-head *C* is connected by means of a tube *f*' with a valve *f*, supported by the fixed rod *b*, which valve by a tube *f*² is connected with a source of supply of carbonaceous or other liquid. (Not shown.) 45 Within the valve *f* is arranged a plunger *f*³, the head *f*⁴ of which is normally held upon its seat *f*⁶ by a spring *f*⁵, as shown in dotted lines in Fig. 8. In the normal position of the plunger *f*³ the communication between the 50 source of supply of carbonaceous or other liquid to the filling-head *C* is closed. Directly below the valve *f* and plunger *f*³ is arranged a rod *g*, guided near its upper end in a plate *g*', secured to the fixed rod *b* of the frame *B*, and near its lower end by the bed-plate *a* and resting with its end upon a bar *g*², carried by brackets secured to the bed-plate *a*, as shown in Fig. 3. The rod *g* at its upper end is provided with a collar *g*³, carrying a 55 plate *g*⁴, which is in slidable engagement with the fixed rod *b* of the frame *B*. Upon the plate *g*⁴ is arranged a second plate *g*⁵, which engages the fixed rod *b* and oscillates thereon, as shown in Figs. 7 and 8. The oscillating 60 plate *g*⁵ is normally held in a position directly below the plunger *f*³ of the valve *f* by a spring *g*⁶ for a purpose to be presently explained.

Below the bar *g*² and secured to the shaft *a*⁸ is a cam *g*⁷, which during a certain portion of its revolution will be brought into engagement with the bar *g*² and will raise the same and the rod *g*, resting thereon. The upward movement of the rod *g* by means of the oscillating plate *g*⁵ will be transmitted to the plunger *f*³ of the valve *f*, which by being 70 raised within the valve *f* will, by its portion or part *f*⁸, open communication between the source of supply of carbonaceous or other liquid with the filling-head *C*, which liquid by means of the tubes *f*' and *f*² will now flow 75 through the passage *c*³ into the filling-chamber *c*⁵ and thence through the gasket *c*⁶ and head *e*' of the bottle *e* into the same. Should the bottle *e* not occupy its proper position upon the table *d*³ or be not upon the table, it 80 follows that a waste of liquid would occur, since the valve *f* is positively operated during each revolution of the cam-shaft *a*⁸. This waste of liquid is obviated by the provision of the yielding table *d*³ for the bottle *e*, with the 85 arm *h* passing through a suitable slot *d*⁹ in the table-support *d*. The arm *h* carries a rod *h*', which is guided by the plates *g*' and *g*⁴ and engages a slot *g*⁸ in the oscillating plate *g*⁵. The rod *h*' is provided with a cam *h*², which is normally held out of engagement with the oscillating plate *g*⁵ as long as the table *d*³ is depressed by a bottle *e*, as illustrated in Figs. 4, 7, and 8. Should, however, a bottle not occupy its position on the yielding table *d*³, 90 the table will be raised by the springs *d*⁵ to the top of the table-support *d*, which upward movement will elevate the arm *h*, the rod *h*', and the cam *h*². The cam *h*² is thereby 95 brought into engagement with the oscillating plate *g*⁵, as illustrated in dotted lines in Fig. 8, and will swing the plate *g*⁵ away from the plunger *f*³ and into the position illustrated in dotted lines in Fig. 7. The upward movement of the actuating-rod *g* will in this instance not be transferred to the plunger *f*³ and the valve *f* will thus remain closed. Adjacent to the liquid-valve *f* and carried by the fixed rod *b* of the frame *B* is arranged a 100 sniff-valve *i*, which is of the same construction and arrangement as the valve *f*. The sniff-valve *i* by means of a tube *i*' is connected with the passage *c*⁴ of the filling-head *C*, and its plunger *i*' at a certain period of time is raised by a rod *i*³, guided in the plates *g*' and *g*⁴ and the bed-plate *a*. The rod *i*³ 105 rests upon a bar *i*⁴, carried by brackets *i*⁵ and *i*⁶, secured to the bed-plate *a*, as illustrated in Fig. 3. Below the bar *i*⁴ on the shaft *a*⁸ is located a cam *i*⁷, which during its revolution elevates said bar *i*⁴ and rod *i*³ and opens the sniff-valve *i* to relieve any excess pressure of the gaseous liquid fed into the bottle *e* into the open air, which excess pressure, as is well known, prevents complete filling of a bottle. 110 By raising and lowering the actuating-bar *i*⁴ for the rod *i*³ on its brackets *i*⁵ and *i*⁶ the cam *i*⁷ will be brought sooner or later into engagement with the same and the sniff-valve *i* will 115 120 125 130

correspondingly be opened for a more or less period of time. The same adjustment can also be applied to the bar g^2 , actuating through the rod g the liquid-valve f , so that the amount of liquid fed to the bottle e can be regulated according to the capacity of the bottle. The passage c^3 of the extension c' of the filling-head C is connected by means of a tube k^4 with the cylinder-head k' of a pump k , the outlet-passage k^2 of which is controlled by a check-valve k^3 , as illustrated in Figs. 1 and 9. The pump k by means of a tube k^7 and a second inlet k^5 , controlled by a check-valve k^6 , is in communication with a source of supply of flavoring extracts or syrups. (Not shown.) Within the pump k is arranged a piston k^8 , which is held in its normal lower position by a spring k^{10} engaging the piston-rod or plunger k^9 . Directly below the piston-rod or plunger k^9 is arranged a rod l , passing through the bed-plate a and guided in a bracket l' , secured to this bed-plate. The upper end of the rod l is provided with a collar l' , supporting a plate l^2 , which is in sliding connection with the fixed rod b' of the frame B , as illustrated in Figs. 1, 2, and 9. Upon the plate l^2 is arranged an oscillating plate l^3 , engaging the fixed rod b' , which plate is provided with an opening l^4 and is normally held out of alignment with the end of the piston-rod or plunger k^9 of the pump k by means of a spring l^5 , as illustrated in Fig. 7. Below the rod l and upon the shaft a^8 is secured a cam l^6 , which at each revolution of the shaft a^8 is brought into engagement with the rod l to raise the same. This upward movement of the rod l is transferred, by means of the oscillating plate l^3 , to the piston k^8 of the pump k , which piston forces a certain amount of the flavoring extract or syrup into the bottle e . By the following downward movement of the piston the valve k^6 , controlling the inlet of the syrup into the pump k , will be raised by the suction action created by the downward movement of the piston, and the syrup will readily flow into the pump. The oscillating plate l^3 is provided with a slot l^6 , engaged by a rod m' , having a cam m^2 , similar to the cam h^2 , carried by the rod h' . The rod m' is carried by an arm m , secured to the yielding table d^3 and passing through a slot d^9 of the support d thereof, as illustrated in Figs. 7 and 9. If the bottle e is placed upon the table d^3 , the same will be held in a depressed position within the support d , and the rod m will remain in its lowermost position, holding the cam m^2 out of engagement with the oscillating plate l^3 . If, however, a bottle e is not placed upon the table d^3 , the table, as previously described, will be raised with its support d , and the rod m , with its cam m' , will swing the oscillating plate l^3 into the position indicated by dotted lines in Fig. 7. In this position the opening l^4 of the plate l^3 will be in alignment with the piston-rod or plunger k^9 , and the cam l^6 and rod l will not actuate the piston k^8 of the pump k , as the piston-rod or

plunger k^9 will now pass through the opening l^4 and for a short distance into the collar l' , and thereby waste of flavoring extracts or syrups that might otherwise be occasioned by the pump k with no bottle upon the table d^2 will be obviated, as well as any waste of carbonaceous or other liquid by the valve f , as hereinbefore described. As illustrated in Fig. 4, the socket c of the filling-head C is traversed by a rod n , projecting into the filling-chamber c^5 and terminating in a hook n' , above which is arranged an arm n^2 , curving outwardly and leaving a space n^3 between the hook n' and arm n^2 . The upper end of the rod n is pivotally secured to a lever n^4 , which at one end is connected by a link n^5 with the yoke b^2 of the frame B and at the other end is pivotally engaged by a link n^6 , connected with a rod n^7 , which rod is guided at its upper and lower ends in the yoke b^2 and bed-plate a , as illustrated in Figs. 1 and 2. The lower end of the rod n^7 is in engagement with a suitable cam-groove arranged in the disk n^8 , secured to the driven shaft a^8 of the machine. This disk imparts to the rods n^7 and n the necessary up-and-down movements. When a bottle e is to be inserted into the filling-head C , the rod n , with its hook n' , as illustrated in Figs. 4 and 5, occupies a position in which the spring-latch o' of a sealing-disk o for the bottle e can be readily placed onto the hook n' . The hook n' remains in this position until the bottle e is filled, after which the same is raised to lift the sealing-disk o into the position indicated by dotted lines in Fig. 4, in which position the disk o is brought into engagement with the interior lower edge of the neck e^3 of the bottle e , preventing thereby the escape of liquid and gas therefrom. After the bottle has been closed by the sealing-disk o the hook n' is again lowered, as illustrated in Fig. 6, in which position the spring-latch o' of the sealing-disk o , now projecting above the bottle, can be readily disengaged from the hook n' .

It will be readily understood that instead of a carbonaceous liquid any other fluid or liquid may be charged or conducted into a bottle by a machine of the present invention and that a stoppered bottle may be used instead of the well-known Hutchinson type of bottle, as illustrated, with the sealing-disk, as shown in the drawings. When a stoppered bottle is used, the stopper may be forced into the neck of the bottle by the rod n without departing from the spirit of my said invention, and further changes as to more or less minor details of the machine may be made from what is illustrated and described without departing from the scope of the said invention.

Having thus described the nature and objects of my invention, what I claim as new, and desire to secure by Letters Patent, is—

1. In a bottle-filling machine, in combination with a filling-head, a yielding support upon which the bottle is placed and located below the filling-head, an inlet for the liquid

- to the filling-head, a valve controlling said inlet, a stem projecting from said valve, a plate arranged to oscillate beneath said stem, a shaft, a cam located on said shaft and arranged normally to operate the valve-stem through said plate to control said valve, a cam arranged on said shaft and adapted to elevate and depress the yielding support, said support having a movement independent of the movement imparted to it by said cam and shaft, and means controlled by the independent movement of said support and arranged to oscillate said plate to disconnect the valve-stem from its operating-cam.
5. In a bottle-filling machine, a filling-head and means for supplying the same with a liquid, a sealing-plunger traversing the filling-head, in combination with a support, a yielding table for the bottle arranged within the support and having a movement independent of said support, means controlled by the operation of the machine and arranged to elevate and depress the support and to reciprocate the sealing-plunger, mechanism actuated by the operation of the machine and arranged to control the liquid-supply to the filling-head and means actuated by the independent movement of the table and arranged to control said mechanism.
10. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
15. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
20. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
25. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
30. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
35. In a bottle-filling machine, a filling-head and means for supplying the same with a liquid, in combination with a support, a yielding table for the bottle arranged within the support and having a movement independent of said support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
40. In a bottle-filling machine, a filling-head, an inlet for liquid to said head and an inlet for syrup to said head, in combination with a support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
45. In a bottle-filling machine, a filling-head, an inlet for liquid to said head and an inlet for syrup to said head, in combination with a support, means controlled by the operation of the machine and arranged to elevate and depress the support, mechanism actuated by the operation of the machine and arranged to control the liquid-supply to the filling-head, and means actuated by the independent movement of the table and arranged to control said mechanism.
- of the machine and arranged to elevate and depress said support, a yielding table for the bottle having a movement in the support independent of the elevation and depression of said support, mechanism actuated by the operation of the machine and arranged to control the liquid and syrup inlets, and means actuated by the independent movement of the yielding table and arranged to control said mechanism.
5. In a bottle-filling machine, a filling-head, an inlet for liquid to said head, a valve controlling said inlet, a plunger controlling said valve, a shaft, and intermediate mechanism adapted normally to elevate and depress said plunger, an oscillating plate interposed normally between the plunger and said intermediate mechanism, a yielding support for the bottle adapted to be elevated and depressed by said shaft, and intermediate means controlled by the support arranged to withdraw said oscillating plate when the support is elevated, whereby operation of said inlet-valve is prevented.
6. In a bottle-filling machine, a filling-head, an inlet for liquid to said head, an inlet for syrup to said head, a valve controlling each inlet, a plunger controlling each valve, a shaft and intermediate mechanisms adapted normally to elevate and depress said plungers, an oscillating plate normally interposed between each plunger and its intermediate operating mechanism, a yielding support for the bottle, means controlled by said shaft for elevating and depressing said support, and intermediate means controlled by the upward movement of the support arranged to withdraw both oscillating plates to thereby prevent the operation of both inlet-valves.
- In testimony whereof I have hereunto set my signature in the presence of two subscribing witnesses.
